UNITED STATES PATENT OFFICE

2,129,777

DEVICE FOR STERILIZING BARBER'S
DUSTER BRUSHRichard R. McGrath, Jefferson, Iowa, assignor of
one-half to Wilber G. Pooley and John V.
Pooley

Application July 16, 1936, Serial No. 90,916

3 Claims. (Cl. 21—88)

This invention relates to means to be used in connection with barbers' duster brushes wherein the bristles of the brush may be thoroughly sterilized each time the brush is used, to thereby overcome one of the greatest objections to the use of this type of brush. Insofar as I know no means has heretofore been provided whereby barbers' duster brushes may be sterilized to prevent the spreading of skin diseases from one customer to the other. It is, therefore, the object of my invention to provide a simple, durable and inexpensive device to be used in connection with a barber's duster brush wherein the bristles of the brush will be entirely enclosed when not in use, in an air-tight container, and in connection therewith efficient means for permitting a volatile sterilization agent such as formaldehyde gas, to penetrate the container in which the bristles are enclosed and subject the bristles to the influence of said gas, and in connection therewith means whereby the brush may easily and quickly be placed in operative position.

More specifically, it is the object of my invention to provide in connection with a barber's brush, a casing slidably mounted on the brush handle in such a manner as to enclose the bristles at such times as the brush is not in use, and in connection therewith a detachable receptacle for containing the sterilization agent which may be easily and quickly placed in position after the bristles of the brush have been closed, and further in connection therewith, means whereby the receptacle will be automatically closed before being removed from the casing so as to prevent the escape of the gas therefrom when the case is not in use.

My invention consists in the construction, arrangement and combination of the various parts of the device, whereby the objects contemplated are attained, as hereinafter more fully set forth, pointed out in my claims, and illustrated in the accompanying drawing, in which:

Figure 1 is a side elevation of my improved device showing the manner in which it is applied to a duster brush for sterilizing the same, the sliding casing and the container being shown in section.

Figure 2 is a side elevation of the same showing the container removed and the casing moved to a position to uncover the bristles of the brush.

Figure 3 is a side elevation of the container for holding the sterilizing agent, a portion of which is broken away to show the manner in which the casing is closed when not in use.

Referring to the drawing I have used the refer-

ence numeral 10 to indicate the handle of a duster brush having at each end a number of spring actuated stop devices 11, the lower end of the handle 10 being provided with an enlarged portion 12 on which the bristles 13 are mounted. 5

Slidably mounted on the handle 10 is a casing 14 which is preferably formed of tubular metal of the same diameter as the enlarged portion 12, the upper end of the casing 14 being provided with an inwardly extending flange 15, having a 10 number of semi-spherical recesses 16 in its inner surface adapted to receive the outer ends of the stop devices 11, secured in the upper end of the handle 10, when the casing 14 is moved to its upper position of movement, as illustrated in 15 Figure 2, to serve the purpose of frictionally holding the casing in its elevated position.

Adjacent to the lower edge of the flange 15 is a gasket 17 formed of flexible material such as rubber, which serves to form an air-tight joint 20 between the handle and the upper end of the casing 14. Supported adjacent to the lower side of the gasket 17 is a second flange 18, also provided with a series of semi-spherical recesses 19 to receive the stop devices 11 located in the 25 lower end of the handle 10, to thereby provide means for supporting the sleeve at its extended position of movement, as illustrated in Figure 1, to enclose the bristles 13.

The lower end of the casing 14 is provided with 30 a screw threaded portion 20 adapted to receive a screw threaded portion 21 of the container 22. The upper end of the inner surface of said container is provided with a valve seat 23 adapted to coact with a valve 24 having a downwardly extending stem 25 yieldably supported in the upright lug 26 carried by the bottom of the container 22, a spring 27 being provided in said lug tending to move the valve to closed position. The upper surface of the valve 24 is provided 35 with a series of upwardly extending lugs 28 adapted to be engaged by the lower edge of the casing 14 as the container 22 is mounted on the lower end of the member 14, said lug 28 causing the valve 24 to be moved to an open position 40 after the casing 22 has been mounted on the lower end of the member 14. The portion of the casing 22 below the valve 24 is filled with fibrous material 29, such as cotton, for receiving a volatile sterilization agent such as formaldehyde. It 45 will readily be seen that the fumes from the sterilization agent may enter the casing 14 and sterilize the bristles 13.

When it is desired to use the brush the casing 22 is removed by simply rotating the same rela- 55

tive to the casing 14 to release the screw threaded portions, which at the same time will permit the valve 24 to move to closed position, thus automatically assuring that the fumes from the 5 container 22 will not enter the room in which the brush is placed. The cotton pad in the bottom of the container serves to prevent the sterilization solution from engaging the bristles of the brush at any time that the brush should be 10 supported in any other position than that illustrated in Figure 1. The gasket 17 serves to prevent any gases from escaping between the member 15 and the handle 10.

Thus it will be seen I have provided a simple, 15 durable and inexpensive device which may be used in connection with a barber's duster brush such as is now in common use, whereby the customer may feel assured that he will not contract some skin disease from the use of said brush.

20 I claim as my invention:

1. In a device of the class described, the combination of a brush having a handle and a brush element secured to one end thereof, a casing slidably mounted on said handle adapted to enclose said brush element when in one position of its movement, a container detachably secured to the outer end of said casing, said container having a valve seat, a valve for said seat, yieldable means for moving said valve to a closed position when the container is detached from said casing, means for automatically moving said valve to an open position as the container is placed in position on said casing, means for seal-

ing the other end of said casing to prevent escape of fluids from said container, and means for supporting a volatile sterilizing agent in the bottom of said container.

2. In a device of the class described, the combination of a duster brush, including a handle and a brush element, a casing slidably mounted on said handle to enclose the brush element at its outer limit of movement, means for yieldably latching the casing either at its upper or lower 10 position of movement, a detachable container secured to the free end of said casing, and means for automatically closing said container on being removed from said casing and for automatically opening the container upon being placed in 15 position on said casing, and a volatile sterilization agent within said container.

3. In a device of the class described, the combination of a duster brush, including a handle and a brush element, a casing slidably mounted 20 on said handle to enclose the brush element at its outer limit of movement, a yieldable packing element between the inner end of said casing and said handle, means for yieldably latching the casing either at its upper or lower position of 25 movement, a detachable container secured to the free end of said casing, and means for automatically closing said container on being removed from said casing and for automatically opening the container upon being placed in position on 30 said casing, and a volatile sterilization agent within said container.

RICHARD R. McGRATH.
